UNITED STATES PATENT OFFICE.

JAMES P. BATTEN, OF SAWTELLE, CALIFORNIA.

FOLDING-BED STAND.

1,355,120.

Specification of Letters Patent.

Patented Oct. 12, 1920.

Application filed April 3, 1920. Serial No. 371,039.

To all whom it may concern:

Be it known that I, JAMES P. BATTEN, a citizen of the United States, residing at Sawtelle, in the county of Los Angeles, 5 State of California, have invented certain new and useful Improvements in Folding-Bed Stands; and I do hereby declare the following to be a full, clear, and exact description of the invention, such as will enable 10 others skilled in the art to which it appertains to make and use the same.

This invention relates to beds, and more especially to those which fold; and the object of the same is to produce a stand or pedestal for pivotally supporting the head portion of a bed frame in such manner that the bed can be let down to horizontal position for use or can be raised to upright position and stood against the wall, when it will occupy very little space.

The improved bed stand forming the subject matter of this invention is described below in connection with a bed frame and its mattress such as are usually employed in 25 structures wherein they fold into a cabinet or the like. Reference is made to the drawings wherein:

Figure 1 is an edge view of this structure showing the bed let down in full lines and 30 raised in dotted lines.

Fig. 2 is an elevation of the stand, showing the bed frame in dotted lines.

In the drawings the letter B designates the bed frame carrying a mattress M which 35 doubtless will be held thereon by straps, the foot of the bed being sustained by hinged legs L resting on the floor F and the head H of the bed standing near the wall W so that the structure can be used as seen in full 40 lines in Fig. 1.

The head portion of this bed is sustained by a stand or pedestal constructed and attached to the bed frame in a detailed manner for purposes more fully explained below.

45 Mounted on casters 1 is a base 2 from sixteen to eighteen inches in diameter, and rising from the center of the base is a standard 3 such as a piece of pipe. Its upper

end is screwed into a T-coupling 4, and from the arms of the latter extend horizontal pipe 50 sections 5. On the standard 3 near the base is a coupling 6 and on the outer ends of the sections 5 are other couplings 7, these couplings being connected by two oblique braces 8, also preferably of pipe. The side 55 rails of the bed frame B, indicated at 10 in Fig. 2, have secured to their under sides straps 11 provided with loops 12 which inclose the pipe sections 5 so that the bed frame is hingedly mounted thereon, and the 60 point of such hinging is about sixteen inches from the head H of the bed, and a trifle more than sixteen inches from the upper face of the base, whereas the latter if it is sixteen inches in diameter has a radius of only 65 eight inches.

It results that the bed may be let down for use as seen in Fig. 1 in full lines, or may be turned on its hinges 12 to a substantially upright position as seen in dotted lines, and 70 then pushed against the wall W, and if we assume that the frame 10 and mattress and bed clothing M have an aggregate thickness of say five inches, it will be clear that when the edge of the base strikes the wall W the 75 top of the bed clothing will stand very near the wall, and thus the bed when out of use will occupy a limited amount of space. It might even be possible to push it into a doorway, assuming that the door into the next 80 room was not being used. The casters permit the structure to be moved about as desired, and permit the same to be drawn out from the wall a little in the evening when the bed is to be turned down for use. The 85 straps 11 and loops 12 constitute hinges which of course can be attached by ordinary screws to the under side of the rails 10 of an ordinary wooden bed frame, or by bolts to the rails of a metal bed frame, and therefore the device can be sold as an article of manufacture and applied by the owner to the bed he already possesses.

What is claimed is:

In a folding bed, the combination with a 95 bed frame, and hinges secured beneath its

side rails at a distance from its head; of a stand including a flat circular base mounted on casters, a single standard rising therefrom, a horizontal bar centrally supported across the top of the standard and having its ends engaged with said hinges, and braces from the lower end of the standard to the outer ends of said bar, the distance from a line through the hinges to the upper face of said base being greater than the dis-

tance from said line to the head of the bed frame and the diameter of said base being less than either.

In testimony whereof I affix my signature in the presence of two witnesses.

JAMES P. BATTEEN.
